TROUSER AND SKIRT HANGER

Henry C. Ehmke, Waterloo, Iowa

Application October 23, 1948, Serial No. 56,185

1. Claim. (Cl. 223—95)

This invention relates to a trouser and skirt hanger.

It is an object of the present invention to provide a trouser and skirt hanger wherein the trouser or skirt does not have to be extended over the hanger bar in such a manner that a crease would be placed in the same and whereby the skirt or trouser can be connected from its upper portion and suspended from the hanger and wherein, if desired, in order to conserve space where there is not room to allow the trouser or skirt to extend its full length, to have clamps which are attachable to the lower ends of the trouser or skirt and which are also attachable to the main body of the hanger.

Other objects of the present invention are to provide a trouser and skirt hanger which is of simple construction, adjustable to different widths of skirts and trousers, inexpensive to manufacture, convenient to use, compact and efficient in operation.

For other objects and for a better understanding of the invention, reference may be had to the following detailed description taken in connection with the accompanying drawing, in which

Fig. 1 is a perspective view of a trouser and skirt hanger formed of spring wire and embodying the features of the present invention.

Fig. 2 is a perspective view of a modified form of hanger having one side arm adjustable to the different size of skirt or trouser.

Fig. 3 is an enlarged longitudinal sectional view taken through the adjustable slide and lock device for the slideable arm, of the form of the invention shown in Fig. 2.

Fig. 4 is a perspective view of a still further form of the invention wherein the slide has a plurality of holes and the arm has a projection adapted to be extended into the holes to hold the slide in its adjusted position.

Fig. 5 is a longitudinal sectional view taken on line 5—5 of Fig. 4.

Fig. 6 is a perspective view of one of the hangers with a pair of trousers thereupon and of a clip clamp extending over the hanger and retaining the bottom end of the trousers.

Fig. 7 is a fragmentary view of a portion of the hanger and showing the clamp in perspective.

Referring now particularly to Fig. 1, there is shown a spring wire 10 formed with a top loop 11 to which a hook 12 is connected. The wire extends laterally from the opposite sides of the loop and one end 13 is formed with a transverse

closed loop construction 14 adapted to be extended through the belt loops of a pair of trousers or skirt. The opposite end of the loop 11 has an extension 15 with a depending loop 16 adapted to be projected into the opposite end of the trousers whereby to make the connection with the same and to straighten out the trousers or skirt upon the hanger. The wire extension 15 can be bent and will spring tightly against the ends of the trousers or skirt.

Referring now particularly to Figs. 2 and 3, there is shown a different form of construction wherein the main body is formed of flat wire 16' which is made into a loop 17 to which is connected a hook 18. The wire extends to one end and is bent laterally as indicated at 19 to fit into a belt loop of trousers or skirt. An angle piece 21 cooperates with the bent end 19 and is secured to the end of the wire so that two such belt loops of the trousers can be supported as shown in Fig. 6. On the opposite end of the wire 16' there is connected a slide 22 having a rounded outer end 23. The slide can be adjusted along the wire and will be held in its adjusted position by a lock device 24. The lock device includes a sleeve 25 and a transverse loop 26 fitted into a curved part 27 of slide 22. A projection 28 of the sleeve 25 may extend under the loop 26 whereby to hold the end 29 spring pressed against the side of the hanger portion. A second sleeve 29 supports the outer end of the extension 22. This sleeve 29 is connected to the outer end of the main portion of the wire 16'. The slide 22 can be moved to any position to properly engage with the end of the skirt or trouser.

In Fig. 4 there is shown a still further form of the invention wherein a straight bar 31 is provided to which there is connected a hook 32. The opposite end of the bar 31 is bent similar to the bar 16' in Fig. 2 to provide a bent end 33 and a member 34 connected to the bar 31. The bent end 33 and member 34 are extended into belt loops 35, Fig. 6.

On the opposite end of the bar 31 is an adjustable slide 36 having a series of longitudinally spaced inclined notches or recesses 37 into which a projection 38 on the outer end of the bar 31 may be extended. To adjust the slide, the same is elevated and moved along and then lowered so that the projection 38 enters the notch or space 37 in the slide, Fig. 5. The outer end of the slide 36 is closed as indicated at 39 and this end fits into the trouser or skirt to retain the same.

As shown in Fig. 6, clamps 41 may be extended

onto the hanger to support lower ends of the trousers. Each clamp 41 is formed like a clothes pin of two parts 42 and 43 having handle portions which are normally urged toward one another by a coil spring 44 having ends 45 and 46 extended onto the parts. The part 43 has a clip 47 adapted to fit over a hanger portion.

While various changes may be made in the detail construction, it shall be understood that such changes shall be within the spirit and scope of the present invention as defined by the appended claim.

Having thus set forth and disclosed the nature of my invention, what is claimed is:

A trouser or skirt hanger comprising a main member, a hook extending upwardly from the main member, one end of the main member having belt loop engaging portions adapted to fit into the belt loops of a pair of trousers or skirt, and an adjustable slide on the opposite end of the main member so that the hanger may be fitted to different size trousers or skirt and locking means extending between the slide and the

main member to hold the slide in its adjusted position, said locking means comprising an upwardly extending projection on the end of said main member, said slide having inclined openings accessible to the upwardly extending projection on the end of the main member, said slide being hollow and the end of the main member slidable therethrough.
